(57) **CLAIM**

The ornamental design for a display screen or portion thereof with icon, as shown and described.

DESCRIPTION

FIG. 1 is a front view of a display screen or portion thereof with icon, showing my new design; and,

FIG. 2 is a front view thereof, in which a mobile terminal in broken line is provided to illustrate an example environment. The broken lines are for environmental purposes only and form no part of the claimed design.

1 Claim, 2 Drawing Sheets(56)
